(57) **CLAIM**

We claim the ornamental design for a sink, as shown and described.

DESCRIPTION

FIG. 1 is a top perspective view of an embodiment of the claimed design;

FIG. 2 is a top plan view of the claimed design of FIG. 1; FIG. 3 is a bottom plan view of the claimed design of FIG. 1; FIG. 4 is a front elevation view of the claimed design of FIG. 1; FIG. 5 is a right-side elevation view of the claimed design of FIG. 1; FIG. 6 is a rear elevation view of the claimed design of FIG. 1; FIG. 7 is a cross-sectional view of FIG. 2; FIG. 8 is another cross-sectional view of FIG. 2; FIG. 9 is detailed bottom perspective view of the claimed design of FIG. 1 showing a left end of a front apron; FIG. 10 is a top perspective view of another embodiment of the claimed design; FIG. 11 is a top plan view of the claimed design of FIG. 10; FIG. 12 is a bottom plan view of the claimed design of FIG. 10; FIG. 13 is a front elevation view of the claimed design of FIG. 10; FIG. 14 is a right-side elevation view of the claimed design of FIG. 10; FIG. 15 is a rear elevation view of the claimed design of FIG. 10; FIG. 16 is a cross-sectional view of FIG. 11; FIG. 17 is another cross-sectional view of FIG. 11; and, FIG. 18 is detailed bottom perspective view of the claimed design of FIG. 10 showing a left end of a front apron. The ornamental design which is claimed is shown in solid lines in the drawings. The broken lines in the drawings are for illustrative purposes only and form no part of the claimed design.

CERTIFICATE OF CORRECTION

PATENT NO. : D655,798 S
APPLICATION NO. : 29/386884
DATED : March 13, 2012
INVENTOR(S) : Miller et al.

Page 1 of 14

It is certified that error appears in the above-identified patent and that said Letters Patent is hereby corrected as shown below:

The Title page, showing the illustrative figures, should be deleted and substitute therefor the attached Title page.

In the Drawings:

Delete figs. 1-18 and substitute therefor the drawing sheets, consisting of figs. 1-18 as shown on the attached pages.

Signed and Sealed this
Seventeenth Day of December, 2013

Margaret A. Focarino
Commissioner for Patents of the United States Patent and Trademark Office
